METAL WEATHER STRIP AND SASH
BALANCE

Martin J. Gossen, Whitefish Bay, Wis.

Application December 8, 1939, Serial No. 308,107

11 Claims. (Cl. 20—52)

This invention relates to improvements in respect to the combined sash balance and weather strip devices disclosed in my prior Patent No. 2,158,963 granted May 16, 1939.

Among the objects of my present invention are the following:

To provide the weather strip devices of the character set forth in my said prior patent with an additional flange formation along one of the longitudinal edges of the device so as to provide in conjunction with the side walls of the slotted tube of the device a three point contact of the weather strip device with the sash to preclude the passage of drafts between the sides of the sash and the side members of the window frame in all positions of the sash within the frame;

To locate the flange formations aforesaid along the edges of the devices adjacent to the parting strips in the frame to provide metal running surfaces for the sashes along the parting strips for ease in sliding the sashes within the frame;

To have the flange formations aforesaid of such dimensions laterally that said flange formations may take the place of the wooden parting strips heretofore employed;

To provide constructions, either by the use of shields or by offsetting the slots in the tubes, to eliminate noise by preventing the coils of the lifting springs catching along the edges of the slots in the sliding of the sashes in the window frame;

To have the shields when used formed of sheet metal and of similar resiliency to the tubes so that the shields may be held in place by yieldably engaging the tubes; and

To have the shields cover the portions of the slots not traversed by the fasteners which connect the lifting elements within the tubes to the sashes through the slots.

Other and further objects of my invention will appear from the following specification taken in conjunction with the accompanying drawings, in which—

Fig. 1 is a fragmentary view of a window frame and sliding sash assembly equipped with sash balance and weather strip devices of my invention;

Fig. 2 is a vertical sectional view with parts broken away and elevation, respectively, taken on line 2—2 of Fig. 1;

Fig. 3 is an enlarged horizontal sectional view taken on line 3—3 of Fig. 2;

Fig. 4 shows one of my improved weather strip and sash balance units applied to a sash, the unit being in elevation and in section, respectively,

to show the location and extent of the shield heretofore referred to.

Fig. 5 is a horizontal sectional view showing a modified form of a weather strip construction to be later described;

Fig. 6 is a similar sectional view showing another modification in respect to the weather strip construction; and

Fig. 7 is a fragmentary perspective view of my improved weather strip element.

In the drawings, 1 indicates generally a window frame, and 2, 3 indicate respectively, upper and lower sashes slidably mounted within said frame in passing relation.

15 The frame has slideways at its side jambs 4, 4 for the sashes. These slideways are provided by the jambs and the cooperating spaced stop strips 5, 6 and 7 as in window constructions of this character. The stop strips extend along the 20 jambs at each side of the frame and also along the header 8 at the top of the frame as shown in Fig. 2. The strips 5 and 7 are the inner and the outer stop strips, respectively, while the strips 6 are between the sashes and constitute the parting strips therefor as shown in Fig. 3. The frame has a sill 9 against which the lower sash 3 seats when closed as shown in Fig. 1.

The combined sash balance and weather strip units of my invention are located at the opposite 30 sides of each sash as in my prior patent aforesaid and as in said patent each unit is comprised of the desired resilient sheet metal material formed to have a slotted tube 10 which extends into a groove 11 in the side rail 12 of the associated sash as shown in Fig. 3. The tubes 10 house the coiled lifting springs 13 for the respective sashes.

The units extend approximately the full height of the frame opening occupied by the sashes and 40 thus the units encompass substantially the full length of the travel of the sashes within the frame. This is likewise true in my prior patent aforesaid, and similarly, the tubes 10 have laterally extending base flanges 14, 14 through which 45 the fastening elements are inserted for securing the tubes to the adjacent side jambs 4 of the frame. In practice only one of the flanges 14 need be used to secure a unit to the frame, although both flanges may be so used should the 50 occasion demand.

The flanges 14 are integrally connected with the base wall 15 of the unit. The base wall 15 extends across the bottom of the tube 10 and seats against the adjacent side jamb of the frame. The base walls 15 and their flanges 14 occupy

the clearance spaces between the frame and the sashes at the sides of the same. The fastening elements referred to are marked 16.

The lifting springs 13, as in my prior patent, are completely housed within the tubes 10 and have hooked formations 17 at their upper ends to connect the springs to the upper ends of the associated tubes. The lower ends of the springs are connected with their associated sashes by fasteners 18 preferably in the form of nails driven into the adjacent side rails of the sashes and extending through the slots 19 in the tubes. The slots 19 extend the full length of the tubes and are formed by terminating short of each other the flange formations 20, 20 along the outer edges of the side walls 21, 21 of the tubes.

The flanges 20 are substantially co-planar and extend over the springs 13 to keep them in the tubes in all positions of sliding adjustment of the sashes within the frame. Due to the slots 19, the side walls 21 of the tubes are free at their outer ends and thus said side walls may be flexed laterally to yieldably engage against the adjacent side surfaces of the sash grooves 11 into which the tubes 10 extend. This tensioning of the side walls 21 is usually done before the tubes are inserted into the sash grooves, and this is done before the sashes are placed in the frame 1. In this way, a sash and its two weather strip units may be arranged in assembled relation without hindrance by the window frame. The customary installing practice is to place the assembly in the frame with the sash at the lower half of the unit as shown in Fig. 4. This leaves the upper half of the unit exposed so that the fasteners 16 may be driven into the frame through one of the flanges 14. The sash is then slid upwardly and the lower portion of the unit is secured to the frame. The spring is in the unit and is connected to the sash before the unit is fastened to the frame.

One feature of my present invention is the provision of an additional flange formation 22 along one longitudinal edge of the unit to engage against the sash in parallelism with the tube 10 to provide in conjunction therewith a three point contact of the unit with the sash. In the embodiment shown, the flange 22 is along the edge of the unit adjacent to the parting strip 6 and lies between said strip and the opposed side face of the sash. This gives the flange 22 the function of providing a metal facing for the parting strip and thus the flange provides a metal running surface for the sash at the parting strip. This precludes the possibility of the sash sticking or binding against the parting strip as the sash runs against a metal surface 22 and not against the wooden parting strip as heretofore.

The flange 22 substantially covers the surface of the parting strip facing the sash and bears against the sash by reason of the spring tension of the tube wall 21 next adjacent said flange urging the sash in the direction of the flange 22. The other tube wall 21 may or may not be sufficiently flexed to engage the sash in the groove 11. If it is so flexed to engage the sash a three point contact is thus provided which precludes the passage of drafts between the sash and the jamb members of the window frame. Hence, any shifting of the sash out of its normal plane will not release all of the contacts and the passage of drafts between the sides of the sash and the frame will be prevented by the contacts which are retained. Moreover, the retained contacts

will be tightened by the shifting of the sash against them. For example, shifting the sash towards the parting strips will tighten the engagement of the contacts at the flanges 22 and the outside walls 21 of the tubes 10. Shifting the sash in the opposite direction will tighten the contact at the inner walls 21 of the tubes and allow the outer walls to flex to retain contact with the sash. It is to be understood that normally the sash is mounted within the frame to engage all three contacts and hence the sash is held by the tubes against any appreciable shifting within the limits of the clearance provided for sliding the sash. The contacts do function, however, in the manner stated in the event any shifting of the sash out of its normal vertical plane should occur. With the sash running against the metal flanges 22 of its respective units, the sash may be raised and lowered with more ease and freedom than when the sash runs directly against a wood parting strip as heretofore. This is important when it is considered that the flange 22 is positioned to engage the sash and that the next adjacent tube wall 21 forces the sash against said flange 22.

As shown in the drawings, the weather strip unit is formed from a single piece of sheet metal. This may be of spring bronze or aluminum, if an aluminum finish is desired. In either case, the flange formation 22 is integrally connected to the base wall 15 and the adjacent flange 14 of the associated tube 10. This gives the flange 22 a double thickness of metal with the fold line 23 between them and along the outer edge of the flange. The wall 24 of the flange directly joins the flange 14 while the wall 25 directly joins the base wall 15 of the tube as shown. This double formation strengthens the flange 22 and holds it in place.

In the devices shown in Fig. 2, the flange walls 24, 25 overlap. This is the construction when a wood parting strip 6 is employed between the flanges 22 of the two adjacent units. In Fig. 5, the flanges 22a, 22a of the two units are formed to occupy the space for a separate parting strip and thus provide a window construction eliminating the need for an independent parting strip. This is accomplished by widening the flanges 22a, their side walls 26, 27 being spaced apart out of contact as shown. The flanges do, however, contact at the meeting points of the two units.

In the units of Figs. 1 to 5 inclusive, the slots 19 in the tubes 10 are centrally disposed between the side walls of the tubes. To prevent the coils of the springs 13 catching on the edges of these slots and producing noise as the springs are expanded and contracted in the sliding of the sashes, I provide a shield element 28 for each tube. Each shield fits within its tube over the slot 19 and closes the slot with respect to the spring in that portion of the tube not traversed by the fastening element 18. This confines the shields 28 to the upper half portions of the tubes as shown in Figs. 2 and 4. This locates the shields over the slots where the coils of the springs are at their normal diameters when contracted. It is here that the springs, if exposed to the slots, would likely catch along the edges of the slots and produce a scraping or scratching noise when expanded. The shields prevent this and, hence, a silently acting unit is provided. The shields need not cover the portions of the slots traversed by the fasteners 18 as the springs reduce in diameter when stretched and

are not likely to catch along the edges of the slots.

Each shield is located within its tube as before stated, and has its body wall 29 extending across the slot 19 in the tube. The side walls 30, 30 of the shield bear against the inner surfaces of the side walls 21 of the tube and by reason of the resilient material of which the shield is made the shield is yieldably held in its position within the tube. The shields may be made to fit the depth and width of the tubes to hold them in place. This brings the side walls 30 of the shield against the tube walls 15 and 21 as shown. The shields are applied to the tubes by inserting the shields into the ends of the tubes, the side walls 30 of the shields yieldingly pressing against the tube walls 21 as the shields are slid into the tubes. The shields are stopped when their upper ends come flush with the upper ends of the tubes as shown in Fig. 4.

The modification shown in Fig. 6 follows the same construction as shown in Figs. 1 to 5. The difference is that no shield element is required to cover the slot in the tube because the slot 31 in the tube 10a is provided along one corner of the tube. This locates the edges of the slot beyond the diameter of the spring 13a and the coils of the spring can not engage the edges of the slot. The fastening element 32 which connects the lower end of the spring to the sash 3a is inserted through the corner slot 31 either at an angle thereto as shown in Fig. 6 or parallel to the adjacent side wall 21b of the tube. In the latter case, the inner end of the fastener would be sufficiently bent or deflected to be engaged with the lower end of the spring. Here the spring has a hook shaped lower end as shown in Fig. 2. In providing the slot 31, the flange 33 on the tube wall 21a extends over the spring, the other tube wall 21b being devoid of a flange formation at its outer end.

The devices shown and described are simple in construction and provide effective weather stripping for the sashes and also lifting devices of the character shown in my prior patent. It 45 may be pointed out that flange formations 22 or 22a not only provide metal running surfaces for the sashes, but being of metal which does not tarnish need not be painted. It is also pointed out that the yielding engagement of tube walls 50 and the flanges aforesaid with the sash develop sufficient friction to hold the sash in any position of adjustment within the frame against the lifting tendency of the springs 13. The latter 55 counter-balances the sashes at intermediate points in their vertical movements. It is to be understood that the weather strip units may be used with or without the shields herein referred to.

It is also pointed out, that the shields when 60 used provide in conjunction with the tubes unbroken bearing surfaces for the springs within the tubes. This gives the springs lateral support and prevents them from rattling in response to vibration. In the particular embodiment shown herein, the bottom wall 15 of a tube provides one bearing surface for a spring, while the shield walls 29 and 30 provide the other bearing surfaces. In practice, the springs are of diameter 65 to fit rather closely within the tubes and hence the continuous bearing surfaces provide for an easy spring action.

The details of construction shown and described may be variously changed and modified without departing from the spirit and scope of

my invention, except as pointed out in the annexed claims.

I claim as my invention:

5 1. In combination, a window frame, a sash slidably mounted within said frame, a metal weather strip device for the sash within the frame and extending substantially the full length of the travel of the sash within the frame, said device being secured to the frame and formed to provide a bottom wall and a slotted tube and a flange formation both extending outwardly from said bottom wall towards the sash, said tube having laterally spaced side walls extending into a groove in the adjacent side portion of the sash, said flange formation extending along one longitudinal edge of the device in spaced relation to the tube and overlapping the adjacent outer side surface of the sash, and a coiled spring for lifting the sash located within the tube, said spring having its upper end in fixed relation to the upper end of the tube and its lower end connected to the sash through the slot in the tube, said device being comprised of resilient sheet metal and the side wall of the tube next adjacent to the flange being tensioned to press and normally hold the sash in sliding contact with the flange with sufficient tightness to hold the sash in any position of sliding adjustment within the frame against the lifting action of the spring.

20 2. In combination, a window frame, a sash slidably mounted within said frame, a metal weather strip device for the sash within the frame and extending substantially the full length of the travel of the sash within the frame, said device being secured to the frame and formed to provide a bottom wall and a slotted tube and a flange formation both extending outwardly from said bottom wall towards the sash, said tube having laterally spaced side walls extending into a groove in the adjacent side portion of the sash, said flange formation extending along one longitudinal edge of the device in spaced relation to the tube and overlapping the adjacent outer side surface of the sash, and a coiled spring for lifting the sash located within the tube, said spring having its upper end in fixed relation to the upper end of the tube and its lower end connected to the sash through the slot in the tube, said device being comprised of resilient sheet metal and the side wall of the tube next adjacent to the flange being tensioned to press and normally hold the sash in sliding contact with the flange with sufficient tightness to hold the sash in any position of sliding adjustment within the frame against the lifting action of the spring, the other side wall of the tube being tensioned to engage the adjacent side surface of the groove and provide in conjunction with the flange and the first mentioned side wall a three point contact of the weather strip device with the sash.

25 3. In combination, a window frame, a sash slidably mounted within said frame, a metal weather strip device for the sash within the frame and extending substantially the full length of the travel of the sash within the frame, said device being secured to the frame and formed to provide a bottom wall and a pair of laterally spaced sash engaging members both extending outwardly from said bottom wall towards the sash, one of said members extending into a groove in the adjacent side portion of the sash and the other member engaging and overlapping an outer side surface of the sash in parallel re-

lation to said groove, and a coiled spring for lifting the sash, said spring having its upper end in fixed relation to the upper end of the bottom wall and its lower end connected to the sash within the groove, said device being comprised of resilient sheet metal and one of said members being tensioned to press and normally hold the sash in sliding contact with the other member with sufficient tightness to hold the sash in any position of sliding adjustment within the frame against the lifting action of the spring.

4. In combination, a window frame, a sliding sash, a metal weather strip device for the sash within the frame and extending substantially the full length of the travel of the sash within the frame, said device being secured to the frame and formed to provide a bottom wall and a slotted tube and a flange formation both extending outwardly from the bottom wall towards the sash, said tube being disposed inwardly from the side margins of the device and having laterally spaced side walls extending into a groove in the adjacent side portion of the sash, said bottom wall extending laterally beyond the side walls and having return bend connections therewith to join the side walls to the bottom wall, said flange formation overlapping an outserside surface of the sash and constituting a folded section of the adjacent return bend connection of the bottom wall, and a coiled spring for lifting the sash located in said tube and having its upper end in fixed relation to the upper end of the tube and its lower end connected to the sash through the slot in the tube, said device being comprised of resilient sheet metal and the side wall of the tube next adjacent to said flange being tensioned to press and normally hold the sash in sliding contact with the flange with sufficient tightness to hold the sash in any position of sliding adjustment within the frame against the lifting action of the spring.

5. In combination, a window frame, a sliding sash, a metal weather strip device for the sash within the frame, said device being secured to the frame and comprised of resilient sheet metal formed to provide a bottom wall and a slotted tube extending outwardly from the bottom wall towards the sash, said tube extending substantially the full length of travel of the sash within the frame and having laterally spaced side walls extending into a groove in the adjacent side portion of the sash, said slot extending the full length of the tube, at least one of said side walls being tensioned to yieldably engage the adjacent side surface of said groove, said side walls having inwardly directed flanges along their outer longitudinal edges to provide the slot in the tube opposite said bottom wall, a coiled spring located within the tube for lifting the sash and held therein by said flanges in all positions of sliding adjustment of the sash within the frame, said spring having its upper end connected to the upper end of the tube and its lower end connected to the sash through the slot in the tube, said spring being stretched and having its coils reduced in diameter on the downward sliding of the sash and being contracted and having its coils enlarged in diameter on the upward sliding of the sash, and means carried by the tube along the edges of the flanges at the slot in that portion of the tube not traversed by the sash connecting means of the spring to prevent the coils of the spring when enlarged catching on the edges of the slot in the sliding of the sash along the tube.

6. In combination, a window frame, a sliding sash, a metal weather strip device for the sash within the frame, said device being secured to the frame and comprised of resilient sheet metal formed to provide a bottom wall and a slotted tube extending outwardly from the bottom wall towards the sash, said tube extending substantially the full length of travel of the sash within the frame and having laterally spaced side walls extending into a groove in the adjacent side portion of the sash, at least one of said side walls being tensioned to yieldably engage the adjacent side surface of said groove, said side walls having inwardly directed flanges along their outer longitudinal edges to provide the slot in the tube opposite said bottom wall, a coiled spring located within the tube to lift the sash and held therein by said flanges in all positions of sliding adjustment of the sash within the frame, said spring having its upper end connected to the upper end of the tube and its lower end connected to the sash through the slot in the tube, said spring being stretched and having its coils reduced in diameter on the downward sliding of the sash and being contracted and its coils enlarged in diameter on the upward sliding of the sash, and a shield element in the form of an elongated strip inserted into the tube between the flanges and the spring and closing the slot in that portion of the tube not traversed by the spring connection with the sash to prevent the coils of the spring when enlarged catching on the edges of the slot in the sliding of the sash along the tube.

7. In combination, a window frame, a sliding sash therein, a metal weather strip device for the sash within the frame, said device being secured to the frame and comprised of resilient sheet metal formed to provide a bottom wall and a slotted tube extending outwardly from the bottom wall towards the sash, said tube extending substantially the full length of travel of the sash within the frame and having laterally spaced side walls extending into a groove in the adjacent side portion of the sash, at least one of said side walls being tensioned to yieldably engage the adjacent side surface of said groove, a coiled spring located within said tube for lifting the sash, said spring having its upper end connected to the upper end of the tube and its lower end connected to the sash through the slot in the tube, said spring being stretched and having its coils reduced in diameter on the downward sliding of the sash and being contracted and having its coils enlarged in diameter on the upward sliding of the sash, and a single flange on the tube along the outer longitudinal edge of one of its side walls and extending towards and terminating short of the other side wall to provide the slot in the tube opposite the bottom wall to one side of the spring to prevent the coils of the spring when enlarged catching on the edges of the slot in the sliding of the sash along the tube.

8. A combined sash balance and weather strip device of the character described comprising, a weather strip element comprised of resilient sheet metal formed to provide a bottom wall to provide a seat for the device, an elongated tube and a flange formation on one side of said bottom wall, said tube having laterally spaced side walls disconnected at their outer ends to provide a slot between them opposite the bottom wall longitudinally of the tube, said bottom wall extending laterally beyond said side walls and having re-

turn bend connections therewith to integrally connect the side walls to the bottom wall, said flange formation extending along one side edge of the tube in spaced relation thereto and being constituted of a folded section of the adjacent return bend connection of the bottom wall to integrally connect the flange to both the bottom wall and the adjacent side wall of the tube, and a sash lifting spring located within the tube and connected at one end to the tube and having its other end available for connection with a sash through the slot in the tube.

9. A weather strip device of the character described comprising, a weather strip element comprised of resilient sheet metal formed to provide a bottom wall to provide a seat for the device and an elongated tube and a flange formation on one side of said bottom wall, said tube having laterally spaced side walls disconnected at their outer ends to provide a slot between them opposite the bottom wall longitudinally of the tube, and said bottom wall extending laterally beyond said side walls and having return bend connections therewith to integrally connect the side walls to the bottom wall, said flange formation extending along one side edge of the tube in spaced relation thereto and being constituted of a folded section of the adjacent return bend connection of the bottom wall to integrally connect said flange to both the bottom wall and the adjacent side wall of the tube.

10. In combination, a window frame, a sash slidably mounted within said frame, a metal weather strip device for the sash within the frame and extending substantially the full length of the travel of the sash within the frame, said device being secured to the frame and formed to provide a bottom wall and a slotted tube and a flange formation both extending outwardly from said bottom wall towards the sash, said tube having laterally spaced side wall members extending into a groove in the adjacent side portion of the sash, said flange formation constituting a wall member extending along one longitudinal edge of the device in spaced relation to the tube

5 and overlapping the adjacent outer side surface of the sash, and a coiled spring for lifting the sash located within the tube, said spring having its upper end in fixed relation to the upper end of the tube and its lower end connected to the sash through the slot in the tube, said device being comprised of resilient sheet metal and having one of said wall members tensioned to press and normally hold the sash in sliding contact with the adjacent wall member with sufficient tightness to hold the sash in any position of sliding adjustment within the frame against the lifting action of the spring.

11. In combination, a window frame, a sash slidably mounted within said frame, a metal weather strip device for the sash within the frame and extending substantially the full length of the travel of the sash within the frame, said device being secured to the frame and formed to provide a bottom wall and a slotted tube and a flange formation both extending outwardly from said bottom wall towards the sash, said tube having laterally spaced side wall members extending into a groove in the adjacent side portion of the sash, said flange formation constituting a wall member extending along one longitudinal edge of the device in spaced relation to the tube and overlapping the adjacent outer side surface of the sash, and a coiled spring for lifting the sash located within the tube, means connecting the upper end of the spring to the upper end of the tube, means connecting the lower end of the spring to the sash through the slot in the tube, said device being comprised of resilient sheet metal and having one of said wall members tensioned to press and normally hold the sash in sliding contact with the adjacent wall member with sufficient tightness to hold the sash in any position of sliding adjustment within the frame against the lifting action of the spring and said tube having its side wall members providing the slot in the tube and overlying the spring to house the same within the tube.

MARTIN J. GOSSEN.
